R. J. PATTERSON.
ELECTRIC HEATER.
APPLICATION FILED NOV. 21, 1921.

1,433,472.

Patented Oct. 24, 1922.

UNITED STATES PATENT OFFICE.

RALPH J. PATTERSON, OF BOSTON, MASSACHUSETTS.

ELECTRIC HEATER.

Application filed November 21, 1921. Serial No. 516,732.

To all whom it may concern:

Be it known that I, RALPH J. PATTERSON, a citizen of the United States, residing at Boston, in the county of Suffolk and State 5 of Massachusetts, have invented certain new and useful Improvements in Electric Heaters, of which the following is a specification.

This invention relates to electric heaters, and more particularly to electric water heaters of the immersion type.

An object of the invention is to provide means for automatically opening the circuit when the heating units or the heating receptacle become overheated due to failure 15 of the water supply or other causes, thus preventing the receptacle and heating unit from being damaged by excessive heat.

In the present invention, I employ a material that is of sufficient conductivity to 20 convey the current from the lead wires to the heating units, but which will melt at a much lower temperature than the material of which the heating elements and the body 25 of the heater are made, whereby the connections will be broken if the water supply is shut off from any cause or excessive over-heating results from any other cause.

A clip of tin, zinc, or an alloy which will melt at a temperature below the temperature 30 necessary to burn out the heating units is secured to the end of each lead wire and in turn connected to the heating units, whereby it is necessary for the current to pass through the clips before reaching the heater.

If the supply of water fails or the device 35 becomes overheated from any other cause, the heat generated melts the clips and breaks the circuit.

In the accompanying drawings, I have 40 shown several embodiments of the invention. In this showing:

Figure 1 is a side elevation, parts being shown in section, of a heater employing a plurality of heating units,

Figure 2 is a plan view thereof,

Figure 3 is a plan view of the heater employing a single heating element.

Figure 4 is a side elevation of a slightly modified form of the invention showing the 50 clip applied to the water outlet pipe,

Figure 5 is a plan view of the form shown in Figure 4 of the drawings, with the cover removed,

Figure 6 is a detail view of the form of

the invention shown in Figures 1 and 2, 55 and,

Figure 7 is a detail view of a lead wire showing the control member in the form of a lug on the end of the wire.

Referring to Figures 1, 2, and 6 of the drawings, the reference numeral 1 designates a suitable receptacle having openings at the top and bottom adapted to be connected to pipes 2, in a water supply line to permit the water to pass through the receptacle. A 60 plurality of heating units 3 are arranged within the vessel or receptacle. These heating units are connected to an electric circuit by means of lead wires 4. A plurality of clips 5 of tin, zinc, or an alloy which is 65 sufficiently conductive to convey the current from the lead wires to the heating units, but which will melt at a low temperature, are connected to binding posts 6, formed on the heating units. As shown, the upper ends 70 of the binding posts may be threaded, as at 7, and these threaded ends are adapted to be passed through openings 8, formed adjacent the ends of the clips and nuts 9 arranged thereon. Intermediate its ends, each clip is provided with an opening 10, adapted 75 to receive a screw 11. The end of the wire is coiled, as at 12, and is adapted to be arranged over the screw 11, a nut 13 being placed on the end of the screw to hold the 80 wire in position. As shown, the lead wires 4 are connected to a pair of clips arranged adjacent each other and a pair of auxiliary lead wires 14 are provided to deliver current to the clips arranged diametrically opposite the clips to which the main lead wires 85 are connected. By referring to Figure 2 of the drawings, it will be seen that the current flows in one of the lead wires and passes to two of the heaters through the 90 first clip, a portion of the current passing through the auxiliary lead wire 14 to the opposite clip. After passing through the heaters, the current passes through the other clips to the other lead wire.

In the form of the invention shown in Figure 3 of the drawings, a single heating unit is employed, having a binding post 15 to which one of the lead wires is directly connected. A clip 16 formed of material 105 similar to that employed in the construction of clip 5 is provided, having an opening adjacent each end. One of these openings is

arranged over the binding post 17 of the heater, and the other lead wire is connected to the opposite end of the clip by means of a screw 18.

5 In the form of the invention shown in Figure 7 of the drawings, a lug 20 is provided on the end of the lead wire, the lug being of the usual construction and having a sleeve 21 by means of which it is secured 10 to the end of the lead wire. The free end of the lug is provided with an opening 22, adapted to be arranged over the binding post of the heater. In the use of the form of the invention shown in Figure 7 of the 15 drawings, the clip 20 may be arranged on either or both of the lead wires.

In the form of the invention shown in Figures 4 and 5 of the drawings, the clip instead of being arranged directly over the 20 heating units, is mounted in a fitting which may be secured to the hot water outlet pipe. The position of the fitting is illustrated in Figure 1 of the drawings arranged over the hot water pipe directly above the heater. 25 As shown, a sleeve 23 is adapted to be arranged over the hot water pipe and this sleeve is provided with a boss or enlargement 24, forming the base of the fitting. A suitable insulating base 25 is arranged within the fitting and a pair of conductor members 26 are supported on this base and spaced from 30 each other. The lead wires 4 are connected to these two strips, the ends of the wires being secured to the conductor members by 35 means of screws 27. The conductor members are further connected to each other by a wire or clip 28 extending across the fitting and connected to each of the conductor members, as at 29. The fitting may be provided 40 with a suitable cover 30, having an opening therein for the reception of a plug 31 of insulating material. The lead wires pass through this plug.

The operation of the device will be apparent. The current normally passes through 45 the clips to the heating units, but if the heating units become overheated, due to any cause, such as the shutting off of the water supply, heat is conveyed by radiation and 50 conduction to the clips which are formed of a material which will melt before the overheating reaches a danger point. When the

clips melt, the circuit is, of course, broken and every danger of overheating is eliminated.

55

In the form of the invention shown in Figures 4 and 5 of the drawings, the heat radiated from the water when the water is heated to an excessive temperature, or radiated through the outlet pipe 2, raises the 60 temperature of the member 28 to the melting point and thus breaks the circuit.

It is to be understood that the forms of my invention herewith shown and described are to be taken as preferred examples of the 65 same, and that various changes in the shape, size, and arrangement of parts may be resorted to without departing from the spirit of the invention or the scope of the subjoined claims.

70

I claim:

1. An electric heater comprising a plurality of heating units, each of said units being provided with a pair of binding posts, fusible clips connecting the adjacent binding posts of said units, and means for connecting a lead wire to each of said clips intermediate its ends.

2. An electric heater comprising a plurality of heating units, each of said units being provided with a pair of binding posts, clips connecting the adjacent binding posts of said units, lead wires connected to alternate clips whereby current will flow through one set of clips to the heating units thence 85 through the other set of clips to the other lead wire.

3. An electric heater comprising a plurality of heating units, each of said units being provided with a pair of binding posts, 90 clips connecting the adjacent binding posts of said units, said clips being formed of a material having a low melting point, lead wires connected to alternate clips whereby current will flow through one of said clips 95 to the heating units thence through the other set of clips to the other lead wire.

In testimony whereof I affix my signature in presence of two witnesses.

RALPH J. PATTERSON.
